United States Patent Office

Des. 212,494
Patented Oct. 22, 1968

212,494

CUTTING BOARD

Francis E. Gruber, 265 Woodlawn Ave.,
St. Paul, Minn. 55105

Filed Oct. 26, 1967, Ser. No. 9,181

Term of patent 14 years

(Cl. D44—1)

FIG. 1

FIG. 2

FIG. 3

FIGURE 1 is a top plan view of a cutting board showing my new design;

FIGURE 2 is an elevational view, partly in section; and

FIGURE 3 is a bottom plan view.

I claim:

The ornamental design for a cutting board, as shown.
